UNITED STATES PATENT OFFICE.

HERBERT N. CHENEY, OF BOSTON, MASSACHUSETTS, ASSIGNOR TO THE GAS MACHINERY COMPANY, OF CLEVELAND, OHIO, A CORPORATION OF OHIO.

CONTROL MECHANISM FOR GAS-SET VALVES.

Application filed October 24, 1924. Serial No. 745,689.

My invention relates to control mechanism for gas-set valves, and particularly to automatic valve-operating mechanism for water-gas sets, such as are shown for example in my co-pending application, Serial No. 729,950, filed August 4, 1924, or in Patent No. 1,497,246, issued to P. Plantinga, June 10, 1924.

The object of the invention is to provide means whereby, when the valve mechanism is set for hand operation, that is when the automatically operating mechanism is inoperative, the operator will not be able to effect a reversion to automatic operation while the set is making gas.

The invention consists of means herein-after fully described and particularly set forth in the claims.

The annexed drawings and the following description set forth in detail certain means embodying my invention, the disclosed means, however, constituting but one of the various mechanical forms in which the principle of the invention may be employed.

In said annexed drawings:

Figure 1 represents a plan of that part of an automatic valve-operating mechanism to which my invention is shown applied.

Fig. 2 represents an end elevation of said mechanism, showing the parts in the position which they occupy while the apparatus is operating automatically.

Fig. 3 represents a view similar to that of Fig. 2, showing the parts in a position in which they are set for hand operation and locked so as to prevent the mechanism from being set to operate automatically.

Fig. 4 represents a transverse section taken upon the plane indicated by line IV-IV, Fig. 1.

The illustrated embodiment of my invention, in so far as concerns the general principles of operation and construction, is exactly like that of the corresponding parts of the above-mentioned Plantinga patented device, with such modifications pertinent thereto as I have shown and described in my above-mentioned pending application, so that a detailed description of the matter common to this application and said prior structure will be unnecessary and hence not indulged in.

Referring now to the structure of said Plantinga patent (lines 85 to 106, page 3)

it will be noted that "locking-out dogs 79" are referred to, their operation described and that when these dogs are raised, they render the automatic mechanism inoperative, as is required when it is desired to manually control the operation of the gas-set valves (see lines 37 to 56, page 4 of the patent).

In this instance similar dogs 79 are provided, one for each of the dogs 70 and 71, fixedly secured to the oscillatory bars 78 and 83, Fig. 4, as in said patented device. Bar 78 is, however, provided, with an arm 1, the free end of which articulates with the lower end of a link 2 whose upper end articulates with an arm 3 forming a part of a hood or basket 4. This hood is provided with brackets 5-5, Fig. 1, which are fixed to journal shafts 6-6 mounted in stationary bearings 7-7 forming a part of the frame of the machine. Secured to one of these shafts 6 is a disk 8, which, with the hood 4, constitute an oscillatory member which, when horizontal, extends over the upper ends of and partly surrounds the handles 45 which are used for manually controlling the valve operations, as described in said patent.

The rods 78 and 83 are each provided at similar ends, with an arm, 80 and 82 respectively, as in the patented device, and these arms are connected with each other by a link 81, Fig. 2.

The arms 1, 80 and 82 are so positioned that when the rod 2 is pulled upwardly the rods 78 and 83 will be turned so as to turn the dogs 79 upwardly and actuate the dogs 70 and 71 to hold the latter out of operative engagement with the timing disks, as shown in dotted lines in Fig. 4.

It will therefore be seen that by raising the hood or basket 4 into an upright position, as shown in Fig. 3, the automatically operating mechanism will be rendered inoperative.

The disk 8 is provided with a peripheral notch 9 which, when the hood is upright, may be engaged by the lip 10 of one end of a pivotally mounted pawl 11, the other end 12 of which rests upon a cam-disk 13 having a peripheral segmental portion 14 of circular form and a cam-segmental peripheral portion 15.

When the pawl-end rests upon the segmental portion 14 the lip 10 may engage the notch 9, and thus lock the hood in its upright position.

Said portion 14 is of a length such that it corresponds in length circumferentially with the longest gas-making period which would ever be desired in the cycle, and the length 5 of the cam-segment 15 corresponds with the length of the shortest blast period which would ever be desired in such cycle. The positions of these two portions of the cam disk are such that the valves of the gas apparatus are set for gas-making during a portion 10 of the time the pawl 11 is in engagement with the segment 14 and set for the blast while in engagement with the segment 15 and during the remainder of the engagement with segment 14.

It will hence be seen that the hood cannot be lowered into the horizontal position and hence automatic operation is prevented while the gas making operation is in progress, but may be so lowered while the set is 20 on the blast.

The automatic operation, however, may be restored during the blast, by lowering the hood, as will be understood from the foregoing description.

Let it be assumed that the apparatus is operating automatically and that the hood is down. In this position, the latter extends over the handles 45 which are used for manually controlling the valves during the "hand operation" of the set, and impedes the manual operation of said handles.

Should it now be desired to effect such operation, the attendant first raises the hood 35 into the position shown in Fig. 3, which exposes the tops or grips of all of the handles so that they may be readily grasped. This act renders the automatically operating part of the mechanism inoperative, as previously 40 described, and should the pawl 11 be in engagement with the segment 14 of the cam disk 13, the lip 10 will engage the notch 9 and lock the hood in such position, thus preventing the hood from being lowered and 45 the automatic operation hence is prevented during the gas-making period of the cycle.

To lower the hood, it is hence necessary to turn the timing disks by hand, or wait until they are turned by the driving mechanism, until the cam-segments 15 lifts the pawl 11 and the latter disengages the disk 8, as shown in Fig. 2, when the hood is then lowered the mechanism reverts to the automatic control of the valves.

55 By having the hood normally above, and as shown, partly enclosing the handle, the attendant is reminded not to manipulate said handles while the mechanism is operating automatically.

60 What I claim is:

1. In a valve operating device, the combination of a plurality of valve-actuating means; a plurality of automatically operated means adapted to render said actuating 65 means operative and inoperative; mechanism

for rendering all of said automatically operated means simultaneously inoperative; means for locking such mechanism in its operative position; and means for automatically actuating said means to assume its unlock- 70 position.

2. In a valve operating device, the combination of means for automatically operating a plurality of valves in a given predetermined cycle; mechanism for simultaneously 75 rendering all of said actuating means inoperative; means for locking said mechanism in its operative position; and means operating throughout a part only of said cycle to automatically actuate said locking 80 means to assume its unlocking position.

3. In a valve operating device, the combination of means for automatically operating the valves; means for manually controlling the operation of said valves; means for rendering said automatic means inoperative and including a manually operable member; means for locking the means which effect such inoperativeness; said manually operable member when the locking means are 85 in inoperative position, being associated with said manually operative controlling means so as to impede their operation.

4. In valve operating device, the combination of means for automatically operating 95 the valves; handles for manually controlling the operation of said valves; means for rendering said automatic means inoperative and including a manually movable hood; and means for locking the means which effect such inoperativeness; said hood when the locking means are in an inoperative position being in proximity to said handles.

5. In a valve operating device, the combination of means for automatically operating 100 said valves and including a plurality of timing disks and dogs controlled thereby, said dogs controlling the actuation of said valves; means for simultaneously actuating said dogs to disengage said disks; a pawl adapted to engage said last-named means whereby said dogs may be held in their disengaging position; and a cam operating synchronously with said disks and adapted to periodically disengage said pawl.

6. In a valve operating device, the combination of means for automatically operating 115 said valves and including a plurality of timing disks and dogs controlled thereby, said dogs controlling the operation of said valves; means for simultaneously actuating said dogs to disengage said disks; a pawl adapted to engage said last-named means whereby said dogs may be held in their disengaging position; a shaft upon which said disks are fixedly mounted; and a cam fixed to said shaft and adapted to periodically engage said pawl to disengage same from said dog-disengaging means.

7. In a valve operating device, the combi- 120

- nation of means for automatically and means for manually controlling the operation of the valves; said manually operative means including a plurality of similarly located handles; means for rendering said automatic means inoperative and including a member adapted to be moved so as to extend over the ends of all of said handles; and a device for locking the means which effect such inoperativeness; the last-named means being inoperative when the said movable member is in position over said handle ends.
8. In a valve operating device, the combination of a plurality of timing disks; a plurality of handles for manually controlling the operation of said valves; a cam rotatable synchronously with said timing disks; a pawl adapted to be oscillated by said cam; a member including a hood adapted to be moved over the ends of said handles and when removed from over said handles to be engaged by said pawl so as to be locked in said described position; and means connected with said member adapted to render said disks inoperative; such last-named means being operative when pawl is in engagement with said member.
9. In a valve operating device, the combination of a plurality of timing disks; a shaft 30 upon which said disks are fixedly mounted; a plurality of handles for manually controlling the operation of said valves; a cam fixedly mounted upon said shaft; a pawl having one end engaging said cam; an oscillatory member including a hood and a disk, the latter being provided with a circumferential notch; means for rendering the automatic valve-operating means inoperative; and means connecting said member with the 40 means for rendering the automatic valve-operating means inoperative; and arranged so as to render the latter operative when said member is lifted; said hood adapted to normally project over said handles; said notch 45 being located so as to engage the other end of said pawl when said hood is lifted and the first-named end of said pawl is out of engagement with said cam.

Signed by me this twenty first day of 50
October, 1924.

HERBERT N. CHENEY.
